UNITED STATES PATENT OFFICE.

EDMUND LICHTENSTEIN, OF BERLIN, GERMANY, ASSIGNOR TO DEUTSCHE MASCHINEN-
ENBAU- UND VERTRIEBS-GESELLSCHAFT M. B. H., OF BERLIN, GERMANY, A FIRM.

DUPLICATING APPARATUS.

Application filed September 26, 1925, Serial No. 58,909, and in Germany October 29, 1924.

This invention relates to duplicating apparatus or the like particularly such as is provided with wiping or moistening and inking mechanisms and has for its primary object to provide against faulty operation thereof.

It has been found that in rotary rubber printing mechanism wherein the rubber cylinder cooperates with a plate cylinder—
10 form cylinder—faulty operation is not rarely produced by reason of the fact that the office operator for operating such printing devices is as a rule insufficiently skilled to effect the starting and stopping of the moistening and inking mechanisms on the 15 form cylinder or in withdrawing it therefrom in the correct sequence.

According to the present invention this is remedied in that the moistening and inking 20 mechanisms are connected or relatively locked by locking devices in such a manner that faulty manipulation is prevented.

In order that the invention may be more clearly understood and readily carried into effect reference may now be had to the accompanying drawings in which a preferred constructional form of the invention is illustrated and in which:—

Fig. 1 shows a sectional elevation of a 30 duplicating apparatus with the moistening and inking mechanisms in operative position.

Fig. 2 shows a sectional elevation of the same duplicating machine in a different 35 vertical plane with the inking mechanism in inoperative position and the moistening mechanism in operative position.

The inking mechanism *b* is adapted to bear against the form cylinder *a* but is 40 adapted to be withdrawn therefrom as for example by being mounted upon a bearing plate *c* pivotally mounted at *d* when desired.

On the other side of the form cylinder *a* and adapted to bear thereagainst are 45 moistening rollers *e*, forming the moistening mechanism, against which bear one or more cleaning rollers *f*. The rollers *e* and *f* are mounted upon a bearing plate *g* pivotally mounted at *h* and are therefore 50 capable of movement into contact with or away from the form cylinder *a*.

The withdrawal of the inking mechanism from the cylinder *a* is effected by a hand lever *i*, adapted to swing on the pivot *k*, and when moved in the direction of the arrow a cam surface *l* thereon acts against a pin *m* on the bearing plate *c* as clearly shown in Figs. 1 and 2. The lever *i* has two teeth or projections *q* or *q'*, staggered peripherally as well as axially. 55 60

When the lever *i* approaches the position shown in Fig. 2 a catch *o*, pivotally mounted at *n*, moves under the action of a spring *z* or the like in the direction of the arrow in the dotted line position shown in Figure 65 2 and engages with its shoulder *p* under the tooth *q* of the lever *i* so that the latter cannot be returned to the position shown in Fig. 1.

The catch *o* however is prevented from 70 moving as above described until a hook *r*, engaging a stationary pin *s* to normally retain the moistening mechanism in the applied position, has been released.

If the moistening mechanism is swung 75 back from the disengaged, dotted line, position, into the position in Fig. 1, then, as shown in Fig. 1, the point of the hook *r* strikes against the lower end of the catch *o* and disengages this so that the lever *i* 80 can be moved into the position shown in Fig. 1 and the inking mechanism applied.

This arrangement ensures that under all 85 conditions the moistening mechanism *e* must be applied before the inking mechanism with the result that the form cylinder is prevented from becoming dry.

The inking and moistening mechanism, however, are further inter-connected by a sector shaped member *t* which is pivoted on 90 the stationary pivot *u* and which co-operates with the parts *q'* and *r*.

When the sector *t* is in the position shown in Fig. 1, its lower end engages over the hook *r* which cannot therefore be disengaged. This position occurs when the projection *q'* assumes the position as shown in Fig. 1. This indicates that the moistening mechanism *e* cannot be withdrawn when the inking mechanism is applied. Again this 100 also ensures that the form cylinder *a* cannot become dry.

When however the lever *i* is moved downwardly from the position in Fig. 1 into that in Fig. 2, i. e., if the inking mechanism is withdrawn, the projection *q* raises the sector *t* by means of its projection *v* into the position in Fig. 2 in which it releases the hook *r*, which is now disengaged for the purpose of enabling withdrawal of the moistening mechanism *e*.

10. What I claim is:—

1. Duplicating apparatus comprising moistening mechanism and inking mechanism and means for preventing movement of the moistening mechanism to inoperative position until after the inking mechanism has been so moved, as well as means for preventing movement of the inking mechanism to operative position until the moistening mechanism has been so moved, both mechanisms being adapted to be so moved independently and free of compulsory connection by common engaging and disengaging means.

2. Duplicating apparatus comprising moistening mechanism and inking mechanism and means for preventing movement of the moistening mechanism to inoperative position until after the inking mechanism has been so moved, as well as means for preventing movement of the inking mechanism to operative position until the moistening mechanism has been so moved, both mechanisms being adapted to be so moved independently and free of compulsory connection by common engaging and disengaging means, both mechanisms blocking each other at an attempt of wrong manipulation.

3. Duplicating apparatus comprising moistening mechanism and inking mechanism and means for preventing movement of the moistening mechanism to inoperative position until after the inking mechanism has been so moved, as well as means for preventing movement of the inking mechanism to operative position until the moistening mechanism has been so moved, both mechanisms being adapted to be so moved independently and free of compulsory connection by common engaging and disengaging means, the moistening mechanism after the

inking mechanism has been moved to inoperative position being freely movable to such an extent as to expose fully its working surface.

4. Duplicating apparatus comprising moistening mechanism, inking mechanism and a pivoted catch co-operating with both of said mechanisms for preventing movement of said moistening mechanism into inoperative position until after the inking mechanism has been so moved.

5. Duplicating apparatus comprising inking mechanism, moistening mechanism, a pivoted catch normally co-operating with the moistening mechanism to hold it in operative position and a handle for moving said inking mechanism having means for causing movement of said catch to release the moistening mechanism as the inking mechanism is moved to inoperative position.

6. Duplicating apparatus comprising inking mechanism, moistening mechanism, a spring biased pivoted catch co-operating with said mechanisms permitting movement of said inking mechanism whilst the moistening mechanism is in operative position but preventing movement of said inking mechanism to operative position when the moistening mechanism has been moved to inoperative position.

7. Duplicating apparatus comprising inking mechanism, moistening mechanism, a handle for moving said inking mechanism from operative to inoperative positions and vice versa, a spring biased pivoted catch co-operating with said mechanisms, a second pivoted catch co-operating with said mechanisms means associated with said handle for moving said last mentioned catch to release said moistening mechanism when the inking mechanism is moved to inoperative position and means also associated with said handle for co-operating with said first mentioned spring biased catch for preventing movement of said inking mechanism to operative position when said moistening mechanism is inoperative.

In testimony whereof I have signed my name to this specification.

EDMUND LICHTENSTEIN.
